UNITED STATES PATENT OFFICE.

WILLIAM S. GRAHAM, OF CANTON, ILLINOIS, ASSIGNOR TO PARLIN & ORENDOFF, OF CANTON, ILLINOIS, A CORPORATION OF ILLINOIS.

GANG-PLOW.

1,163,143.

Specification of Letters Patent.

Patented Dec. 7, 1915.

Application filed February 10, 1915. Serial No. 7,285.

To all whom it may concern:

Be it known that I, WILLIAM S. GRAHAM, a citizen of the United States, residing at Canton, in the county of Fulton, State of Illinois, have invented certain new and useful Improvements in Gang-Plows, of which the following is a specification, reference being had to the accompanying drawings.

This invention relates to gang plows, and especially to that "frameless" type of gang plow adapted to be drawn by a traction engine, and comprising two or more plow-beams rigidly tied together for forming the plow frame, the plow-bodies being adapted to be moved into and out of operative plowing position by swinging the supporting wheels up or down relative to the plow-beams.

It is one of the objects of my invention to utilize, in a plow of this type, the traction power of one of the supporting wheels for moving said wheels downward for throwing the plow-body out of engagement with the ground, suitable connections being provided between the supporting wheel from which power is taken and the mechanism for raising the plow-bodies whereby the bodies are raised gradually, as desired, from operative position.

It is another object of my invention to so arrange the mechanism of a plow of the type just referred to that the raising of the rigidly-tied plow-beams may be timed in such a manner that the successive bodies of the series may be caused to run out of the ground successively so as to leave an approximately even-ended furrow.

It is another object of my invention to provide a plow having such an arrangement of parts that the plow-bodies shall be caused to move downward into operative position by their own weight and by the suction of the plow-bodies in the ground, suitable yielding means being employed for assisting in lifting the plows out of operative engagement with the ground, such yielding means being adjusted to such effective strength as not to interfere with the proper lowering of the plow through the medium of its weight and its suction in the ground.

It is another object of my invention to provide a construction embodying the features above set forth so arranged that the ground wheel from which power is taken shall be able to raise the plows out of operative position without the necessity for providing such ground wheel with cleats or other projecting parts for gripping the ground, this object being accomplished in the construction shown by the employment of speed-reducing gearing between the ground wheel and the plow-raising mechanism.

It is another object of my invention to provide such a form and arrangement of parts, in a plow of the type described in which the plow-bodies descend by their own weight into operative position, that the downward movement of the plows shall be limited so as to cause the successive bodies of the series to engage the ground successively approximately on a line at right angles to the advance of the plow.

It is another object of my invention to improve gang plows in sundry details hereinafter pointed out.

The preferred means by which I have accomplished my several objects are illustrated in the accompanying drawings and are hereinafter specifically described.

That which I believe to be new and desire to cover by this application is set forth in the claims.

In the drawings,—Figure 1 is a top or plan view of a plow embodying my improved construction; Fig. 2 is a side view of my improved plow, with the land wheel omitted therefrom for the sake of clearness of illustration; Fig. 3 is an enlarged detail of certain of the plow-raising elements, being substantially a section taken on line 3—3 of Fig. 1; Fig. 4 is a side view similar to Fig. 2, but showing the plow-bodies in raised position; Fig. 5 is an enlarged detail, being a perspective view of the sleeve and segmental rack construction employed in connection with the plow-raising mechanism; Fig. 6 is an enlarged detail, being a cross-section through the clutch, as viewed from the side thereof upon which the beams are

located, showing the clutch in inoperative position; and Fig. 7 is a view similar to Fig. 6, but showing the clutch in operative engagement.

- 5 Referring to the several figures of the drawings, in which corresponding parts are indicated by the same reference characters, 10—11 indicate plow-beams arranged side by side, tied together at their forward ends 10 by a transverse brace 12 and tied together near their rear ends by a diagonally-disposed brace 13. Plow-bodies 14—15 are mounted in any suitable manner upon the rear ends of the beams 10—11, respectively, 15 in suitable coöperative position.
- 16 indicates a rear furrow-wheel mounted by means of an axle-member 17, a sleeve 18, a swinging link 19, and a bracket 20 upon the plow-beam 11 behind the plow-body 15.
- 20 A lever 21 is pivotally mounted upon the bracket 20, the lower turned end of which is pivotally connected with an arm 22 fixed upon the sleeve 18. As will be appreciated by reference to Figs. 2 and 4, by a rearward 25 movement of the lever 21 out of the position shown in said figures, the wheel 16 would be depressed relative to the plow-beam 11, serving to lift the plow-beams relative to said wheel for purposes of trans- 30 portation of the plow. Inasmuch as the lifting mechanism just described forms no part in and of itself of my present invention, it is not believed to be necessary to describe it further herein.
- 35 At their forward ends the plow-beams 10—11 have fixedly connected to them in any suitable manner extension-plates 23—24, respectively, to the forward ends of which are secured vertical hitch-straps 25 from 40 which draft-bars 26 of any suitable type extend forward for connection to a tractor.
- Revolutely mounted in suitable bearings in the rear ends of the extension plates 23—24 is an axle-member 27, upon an off- 45 set laterally-extending portion 28 of which is suitably journaled a supporting wheel 29. Revolutely mounted in suitable brackets 30—31 carried by the beams 10—11 in rear of the axle 27 is another axle 32 upon 50 an offset laterally-extending portion 33 of which is journaled a supporting wheel 34. As will be readily understood from an inspection of Figs. 2 and 4, when the shaft 27 is rocked in clockwise direction in Fig. 55 2 and the shaft 32 is rocked in counter-clockwise direction in said Fig. 2, the plow-beams 10—11 are raised relative to the supporting wheels 29 and 34, causing the plow-bodies 14—15 to run out of operative en- 60 gagement with the ground. Fixed upon the shaft 27 and rising therefrom is an arm 35 connected by means of a coiled spring 36 with an arm 37 mounted upon the plow-beam 11 rearwardly of the arm 35, said 65 spring serving to assist in the turning of

the shaft 27 in clockwise direction in Fig. 2 for raising the plow-bottoms.

The means for turning the shafts 27 and 32 for effecting the raising of the plows out of operative engagement with the ground or for permitting the plows to move downward by their own weight comprises a drum-like clutch member 38 rotatably mounted by means of a hub 39 and a web 40 upon a pin 41 extending laterally from the bracket 31, 75 said clutch member 38 being provided upon its outer periphery with sprocket-teeth comprising a gear 42, and being provided about its inner periphery with a series of rounded notches or grooves 43. The clutch-member 80 38 is adapted to be continuously driven in counterclockwise direction in Figs. 2 and 4 by means of a sprocket-chain 44 meshing with the gear 42 upon said clutch-member and operating upon a gear 45 which is fixed 85 in any suitable manner upon the hub of the land-wheel 34, or is otherwise suitably connected to said hub so as to rotate therewith. Inasmuch as the clutch-member 38, which is connected by the chain 44 with the gear 45 90 mounted upon the spindle portion 33 of the axle 32, is not mounted upon the axis of rotation of the shaft 32 as it is rocked for raising and lowering the plow-bodies, I have provided yielding means for taking 95 up the slack of the chain 44. Such yielding means comprises an arm 46 pivotally mounted upon a corner-block 47 suitably secured upon the axle-member 32, said arm being provided at its free end with a laterally-extending roller 48 revolvably mounted thereon in position to engage the lower 100 face of the chain 44. A spring 49 is connected to the arm 46 and to an arm 50 projecting from another corner-block 51 fixed upon said axle-member 32, said spring 49 serving to hold the arm 46 in a position to take up the slack in the chain, as will be readily understood.

Revolutely mounted upon the pin 41 adjacent to the clutch-member 38 is a plate 52 provided at its ends with rounded openings 53—54, as best shown in Figs. 6 and 7. Pivotally mounted upon the plate 52 is a double-ended dog 55 having revolvably mounted thereon a roller 56 adapted to engage any one of the grooves or notches 43 of the clutch-member 38, a spring 57 being suitably connected to said dog and to the plate 52 for holding the dog yieldingly in turned position to maintain engagement of the roller 56 with the clutch-member 38. As will be readily understood, the arrangement is such that when the clutch-member 38 is driven in clockwise direction in Figs. 6 115 and 7 with the roller 56 in engagement with one of the rounded notches 43 of the clutch-member, the plate 52 will be rotated in the same direction therewith. As is usual in 120 clutches of this type, means is provided for

holding the roller 56 out of engagement with the clutch-member 38 as desired, such means comprising a roller 58 adapted to engage either one of the rounded openings 53 and 54 of the plate 52, the roller when in such engaging position serving to hold the dog 55 turned against the action of the spring 57 into the position shown in Fig. 6. This roller 58 is revolvably mounted upon one end of the lever 59 fixed upon a sleeve 60 revolvably mounted upon a pin 61 fixed upon and extending laterally from the upper end of the bracket 31. Fixed upon said sleeve 60 and extending upwardly therefrom is a lever 62 (see Fig. 2) having connected to its upper end a cord or cable 63 extending under a suitable pulley 64 revolvably mounted upon the extension-plate 24, said cord 63 being adapted to extend forward to the tractor into convenient reach of the operator. An arm 65 (see Fig. 3) is also mounted upon the sleeve 60 and extends diagonally downward therefrom, having connected to its lower end one end of a coiled spring 66, the other end of which is adjustably connected in any suitable manner to a stationary part of the framework, being secured in the construction shown to the bracket 31. The spring 66 serves to hold the lever 62 and the lever 59 turned to the limit of their movement in clockwise direction in Figs. 2 and 4, and to hold the lever 59 turned to the limit of its movement in counterclockwise direction or toward the clutch-member 38 in Figs. 6 and 7.

As will be readily understood, with the roller 58 in engagement with one of the openings or sockets 53-54 of the plate 52, holding the roller 56 out of operative engagement with the clutch-member 38, a forward pull upon the cord 63 by the operator will serve to swing the levers 62 and 59 in counterclockwise direction in Figs. 2 and 4 against the action of the spring 66, withdrawing the roller 58 from its engagement with the socket 53 or 54 and permitting the spring 57 to move the roller 56 into operative engagement with the clutch-member 38. As will be readily understood by those familiar with this type of clutch, when the plate 52 has made substantially a half rotation with the clutch-member 38, the roller 58, which will have been returned by the spring 66 to its normal position relative to the pin 41, will be engaged by one of the cam portions 67 of the plate 52, causing the roller 58 to move outward upon the cam face. Upon the continued rotation of the plate 52, the roller 58 is brought into contact with one end of the dog 55, whereupon a slight additional rotative movement of the plate 52 serves to throw the roller 56 out of operative engagement with the clutch-member 38, thus stopping the rotation of the plate 52. As is readily understood, the

plate 52 may be given as many half rotations as may be desired by successive actuations of the lever 62 at proper intervals by means of the cord 63, or in any other suitable manner.

I will now describe the connections between the plate 52 and the shafts 27 and 32 whereby such shafts may be rocked through the medium of the said plate for raising the plow-bodies. 68 indicates a sleeve (see Figs. 1 and 5) revolvably mounted upon the shaft 27, having secured thereto at one end a segmental rack 69 and at the other end an arm 70. 71 indicates a lever fixed upon the squared end of the shaft 27 adjacent to the segmental rack 69, said lever being adapted to be locked by a spring-latch 72 of any suitable type in any desired position upon said rack. To the rear end of the arm 70 is pivotally connected a link 73, the lower end of which link is pivotally connected to the corner-block 47 mounted upon the axle-member 32. A sleeve 74 is pivotally mounted in any suitable manner upon a horizontal axis upon an arm 75 formed with the segmental rack 69. A connecting link 76 is slidably mounted in said sleeve, being provided with a head 77 on its forward end for preventing its withdrawal from the sleeve 74, and having its rear end pivotally connected with the plate 52.

In operation, when the plate 52 is given a half rotation in counterclockwise direction from the position shown in Fig. 2, the segmental rack 69 will be swung backward through the medium of the link 76, carrying with it the arm 70. Inasmuch as the shaft 27 is locked relative to the segmental rack 69 by the lever 71, the backward swinging of the rack 69 will cause the shaft 27 to rock in clockwise direction in said Fig. 2, causing the furrow-wheel 29 to be moved forward relative to the plow-beams and raising the plow-beams into the position shown in Fig. 4, the spring 36 serving to assist in such operation. At the same time, through the medium of the link 73 connected to the arm 70, the axle-member 32 will be rotated in counterclockwise direction in said Fig. 2, causing the land-wheel 34 to move downward and backward, bringing its spindle portion 33 to substantially the same height as that then assumed by the spindle portion 28 of the axle-member 27. Inasmuch as the sprocket-gear 45 is of considerably smaller diameter than that of the sprocket-gear 42, the rocking of the axles 27 and 32 will be comparatively slow, the requisite power for raising the plows being thus attained without the necessity for providing the land-wheel 34 with cleats or other extensions for the purpose of increasing its grip upon the ground. In the construction shown, the gear 45 is of just half the diameter of the gear 42, but it will be under

stood that in practice the relative sizes of these sprocket-gears may be regulated as desired. As will be readily understood, upon the plate 52 being given another half rotation in counterclockwise direction after the parts have assumed the position shown in Fig. 4, the link 76 will be moved forward relative to the segmental rack 69, permitting the axle-members 27 and 32 to swing again 10 into the position shown in Fig. 2, being actuated for such movement by the weight of the plows and the machine as a whole, and being actuated further by the suction of the plows in the ground.

15 Mechanism is provided for regulating the depth at which the bodies shall work in the ground, by the operation of which the plow bottoms may be raised manually out of their engagement with the ground, if desired.

20 This mechanism comprises a lever 78 revolvably mounted upon the axle-member 27 adjacent to the arm 70, the lever 78 being pivotally mounted, in the construction shown, by means of a socket-member 79. The 25 socket-member 79 and the arm 70 are provided with cooperating stops 80—81, respectively, adapted to engage each other as shown in Fig. 3. The lever 78 is provided with a spring-latch 82 of any suitable type 30 adapted to engage a segmental rack 83 mounted upon the extension-plate 24. The lever 78 is adapted to be held in any desired position relative to the segmental rack 83 serving to limit the counterclockwise 35 movement of the arm 70 in Fig. 3, and thus serving to limit the upward movement of the ground wheels for regulating the depth at which the plow-bodies are permitted to work in the ground. As is shown in Fig. 2, 40 the link 76 is of sufficient length to permit the lever 78 to be set at its extreme forward position. When the lever 78 is moved to a position in rear of its foremost position for limiting the depth of plowing, the first portion 45 of the movement of the plate 52 for raising the plow-bodies has no effect upon the mechanism other than to slide the link 76 through the sleeve 74. When in the continued rotation of the plate 52 the head 77 50 of the link comes into contact with the sleeve 74, the effective lifting operation begins.

By a selection of the sprocket-gear 45 of the required size relative to the size of the sprocket-gear 42; I am enabled to regulate 55 the rate of raising and lowering the plows relative to the forward movement of the plow as a whole. Inasmuch as the plows move out of the ground successively on being raised and move into the ground in the same succession on being lowered, I am enabled to cause the plows to leave the ground at substantially a line at right angles to the direction of plowing, and likewise to enter the ground at substantially a line at right 60 angles to the direction of plowing.

That which I claim as my invention, and desire to secure by Letters Patent, is,—

1. In a plow, the combination of a plow-beam, a plow-body fixed thereon, a ground-wheel mounted on said plow-beam and movable up and down relative thereto, means for moving said ground-wheel vertically relative to said plow-beam, driving means adapted to be connected with said ground-wheel and to be operated thereby, and means for 70 operatively disconnecting said driving means from said ground-wheel upon a certain predetermined actuation of the driving means by said ground-wheel after the connection of said driving means with the 80 ground-wheel, said driving means being adapted by a single complete actuation thereof by said ground-wheel to act upon said wheel-moving means for raising said plow-beam and adapted upon its next-successive single actuation by said ground-wheel to move independently of said wheel-moving means. 85

2. In a plow, the combination of a plow-beam, a plow-body fixed thereon, a ground 90 wheel mounted on said plow-beam and movable up and down relative thereto, means for moving said ground wheel vertically relative to said plow-beam, yielding means tending to move said ground wheel downward 95 relative to said plow-beam, driving means adapted to be connected with said ground wheel and to be operated thereby, means for operatively disconnecting said driving means from said ground wheel upon a certain predetermined actuation of the driving 100 means by said ground wheel after the connection of said driving means with the ground wheel, and means for connecting said wheel-moving means with said driving 105 means, said connecting means being adapted to act positively upon the beam-raising movement of the driving means but adapted to yield upon the movement of the driving means for permitting the lowering of the 110 plow.

3. In a plow, the combination of a plow-beam, a plow-body fixed thereon, a ground wheel mounted on said plow-beam and movable up and down relative thereto, means for moving said ground wheel vertically relative to said plow-beam, driving means, means for connecting said driving means with said ground wheel for operating the driving means, said connecting means comprising speed-reducing gearing and clutching means for operatively disconnecting said driving means from said ground wheel upon a certain predetermined actuation thereof by said ground wheel after its connection with the driving means, and means for connecting said wheel-moving means with said driving means, said connecting means being adapted to act positively upon the beam raising movement of the driving means but adapted 125 130

to yield upon the movement of the driving means by which the lowering of the plow is permitted.

4. In a plow, the combination of a plow-beam, a plow-body fixed thereon, a ground wheel mounted on said plow-beam and movable up and down relative thereto, means for moving said ground wheel vertically relative to said plow-beam, driving means, 10 means for connecting said driving means with said ground wheel for operating the driving means, said connecting means comprising a gear driven by the rotation of said ground wheel, a comparatively larger gear 15 adapted to be driven continuously by said first-named gear, and clutching means interposed between said last-named gear and said driving means for operatively disconnecting said driving means from said 20 ground wheel upon a partial revolution of said second-named gear after its connection with the driving means, and means for connecting said wheel-moving means with said driving means, said connecting means being 25 adapted to act positively upon the beam-raising movement of the driving means but adapted to yield upon the movement of the driving means by which the lowering of the plow is permitted.
5. In a plow, the combination of a plow-beam, a plow-body fixed thereon, a ground wheel mounted on said plow-beam and movable up and down relative thereto, means for moving said ground wheel vertically 30 relative to said plow-beam, driving means adapted to be connected with said ground wheel and to be operated thereby, means for operatively disconnecting said driving means from said ground wheel upon a certain predetermined actuation of the driving means by said ground wheel after the connection of said driving means with the ground wheel, means for connecting said wheel-moving means with said driving means, said connecting means being adapted to act positively 35 upon the beam-raising movement of the driving means but adapted to yield upon the movement of the driving means by which the lowering of the plow is permitted, and 40 adjustable means for limiting the downward movement of the plow-beam for regulating the depth of plowing.

6. In a plow, the combination of a plow-beam, a plow-body fixed thereon, a ground wheel mounted on said plow-beam and movable up and down relative thereto, means for moving said ground-wheel vertically relative to said plow-beam, driving means adapted to be connected with said ground-wheel 45 and to be operated thereby, means for operatively disconnecting said driving means from said ground-wheel upon a certain predetermined actuation of the driving means by said ground-wheel after the connection of said driving means with the ground-

wheel, and means for connecting said wheel-moving means with said driving means, said connecting means being adapted to act positively upon the beam-raising movement of the driving means but adapted to yield upon 70 the movement of the driving means for permitting the lowering of the plow.

7. In a plow, the combination of a plow-beam, a plow-body fixed thereon, a ground-wheel mounted on said plow-beam and movable up and down relative thereto, means for moving said ground-wheel vertically relative to said plow-beam, a rotatable plate adapted to be connected with said ground-wheel and to be rotated thereby, and means 75 for connecting said wheel-moving means with said rotatable plate, said connecting means being adapted to act positively upon the portion of the revolution of the rotatable plate for raising the plow-beam but adapted to yield upon the remaining portion of a complete revolution of the plate.

8. In a plow, the combination of a plow-beam, a plow-body fixed thereon, a ground-wheel mounted on said plow-beam and movable up and down relative thereto, means for moving said ground-wheel vertically relative to said plow-beam, and an actuating member adapted to be driven by power from said ground-wheel and adapted by a movement in one direction to act upon said wheel-moving means for raising the plow-beam but adapted to move in the opposite direction independently of said wheel-moving means.

9. In a plow, the combination of a plow-beam, a plow-body fixed thereon, a ground-wheel mounted on said plow-beam and movable up and down relative thereto, means for moving said ground-wheel vertically relative to said plow-beam, a rotatable plate adapted to be connected with said ground-wheel and to be rotated thereby, and a link pivotally connected with said plate and having a sliding connection with said wheel-moving means adapted to act positively upon said wheel-moving means upon the portion of the revolution of the plate for raising the plow-beam but adapted to yield relative to the wheel-moving means 110 upon the remaining portion of a complete revolution of the plate.

10. In a plow, the combination of a plow-beam, a plow-body fixed thereon, a ground-wheel mounted on said plow-beam and movable up and down relative thereto, means for moving said ground-wheel vertically relative to said plow-beam, a rotatable plate adapted to be connected with said ground-wheel and to be rotated thereby, and a link 120 pivotally connected with said plate and having a sliding connection with said wheel-moving means adapted to act positively upon said wheel-moving means upon the portion of the revolution of the plate for 125 130

raising the plow-beam but adapted to yield relative to the wheel-moving means upon the remaining portion of a complete revolution of the plate, the connection between 5 said rotatable plate and said ground-wheel comprising a clutch adapted automatically to effect a disconnection at each half revolution of the plate.

11. In a plow, the combination of a plow-beam, a plow-body fixed thereon, a ground-wheel mounted on said plow-beam and movable up and down relative thereto, means for moving said ground-wheel vertically relative to said plow-beam comprising an 15 arm adapted to be swung about a horizontal axis, and a link in rear of said arm adapted to be reciprocated longitudinally of the plow by power from said ground-wheel, said link having a sliding connection with said arm 20 whereby it is free to move forward relative to said arm but is limited in its rearward movement relative to the arm.

12. In a plow, the combination of a plow-beam, a plow-body fixed thereon, a ground-wheel mounted on said plow-beam and movable up and down relative thereto, means for moving said ground-wheel vertically relative to said plow-beam comprising an arm adapted to be swung about a horizontal 25 axis, a link in rear of said arm adapted to be reciprocated longitudinally of the plow by power from said ground-wheel, said link having a sliding connection with said arm whereby it is free to move forward relative 30 to said arm but is limited in its rearward movement relative to the arm.

13. In a plow, the combination of a plow-beam, a plow-body fixed thereon, an axle-member revolvably mounted transversely relative to said plow-beam, a ground-wheel revolvably mounted on an offset portion of 45 said axle-member, an arm carried by said axle-member, by the swinging of which arm said axle-member is rotated for raising said plow-beam, and a link in rear of said arm adapted to be reciprocated longitudinally of 50 the plow by power from said ground-wheel, said link having a sliding connection with said arm whereby it is free to move forward relative to said arm but is limited in its rearward movement relative to the arm.

14. In a plow, the combination of a plow-beam, a plow-body fixed thereon, a ground-wheel mounted on said plow-beam and movable up and down relative thereto, means for moving said ground-wheel vertically relative to said plow-beam comprising an arm adapted to be swung about a horizontal axis, a link in rear of said arm adapted to be reciprocated longitudinally of the plow by power from said ground-wheel, said link 60 having a sliding connection with said arm 65

whereby it is free to move forward relative to said arm but is limited in its rearward movement relative to the arm, adjustable means for limiting the forward swinging of the arm for regulating the depth of plowing, and an adjustable stop-device carried by said plow-beam adapted to limit the swinging of said axle-member for regulating the depth of plowing. 70

15. In a plow, the combination of a plow-beam, a plow-body fixed thereon, an axle-member revolvably mounted transversely relative to said plow-beam, a ground-wheel revolvably mounted on an offset portion of the axle-member, an arm carried by said 80 axle-member and adjustable relative thereto, by the swinging of which arm said axle-member is rotated for raising said plow-beam, and a link in rear of said arm adapted to be reciprocated longitudinally of the 85 plow by power from said ground-wheel, said link having a sliding connection with said arm whereby it is free to move forward relative to said arm but is limited in its rearward movement relative to the arm. 90

16. In a plow, the combination of a plow-beam, a plow-body fixed thereon, two axle-members revolvably mounted transversely relative to said plow-beam, ground-wheels revolvably mounted on offset portions of said 95 axle-members respectively, connections between said axle-members for causing them to swing together, said connections comprising means for adjusting one axle-member relative to the other, an arm carried by one 100 of said axle-members and adjustable relative thereto, by the swinging of which arm said axle-members are rotated for raising said plow-beam, a link adapted to be reciprocated longitudinally of the plow by power 105 from one of the ground-wheels, and connections between said link and said arm whereby upon the movement of said link to the rear said arm is actuated for raising said plow-beam and whereby upon a forward movement of the link said link is free to 110 yield relative to the arm.

17. In a plow, the combination of a plow-beam, a plow-body fixed thereon, two axle-members revolvably mounted transversely 115 relative to said plow-beam, ground-wheels revolvably mounted on offset portions of said axle-members respectively at opposite sides of the plow, an arm revolvably mounted on one of said axle-members, a segmental rack mounted adjacent to said arm and adapted to swing therewith about said axle-member, a lever fixed on said last-mentioned axle-member adjacent to said segmental rack and adapted to operatively engage said rack 120 in any desired adjusted position thereon, a link pivotally connecting said arm with the other of said axle-members for causing said axle-members to swing together, a second link adapted to be reciprocated longitudi- 125 130

nally of the plow by power from one of the said ground-wheels, connections between said second link and said arm and segmental rack whereby upon the movement of said link in one direction said arm is actuated for raising said plow-beam and whereby upon a movement of the link in the opposite direction said link is free to yield relative to the arm, a segmental rack carried by the 10 plow-beam adjacent to said swinging arm, a lever adapted to swing adjacent to said

segmental rack but adapted to be locked in adjusted position relative thereto, and stops carried by said lever and said arm adapted to limit the swinging of said arm in the 15 direction in which the arm moves for lowering the plow-beam.

WILLIAM S. GRAHAM.
